LOOP-TAKER TRANSMISSION MECHANISM
FOR TURNING STITCHING SEWING MA-
CHINESArthur N. Hale, Stratford, Conn., assignor to The
Singer Manufacturing Company, Elizabeth,
N. J., a corporation of New Jersey

Application May 10, 1944, Serial No. 534,886

14 Claims. (Cl. 112—66)

The invention relates to turning stitching sewing machines as of the type in which the needle, in addition to its other motions, is adapted to be rotated and in which a rotary loop-taker and its support are likewise bodily rotated to maintain the required relationship between the needle and the plane of rotation of the beak of the loop-taker, that is, to maintain the correct directional approach of the beak to the needle loop in all rotational positions of the needle.

In a typical machine of this general character, the loop-taker rotating in a vertical plane, is mounted on a horizontal drive shaft to which is secured a bevel gear meshing with a second bevel gear driven through appropriate transmission from the main drive shaft. The horizontal loop-taker shaft is supported on a suitable turret for progressive bodily rotation in a horizontal plane. Such rotation, unless compensated for, causes the first bevel gear to roll on the second bevel gear, thereby rotating the loop-taker shaft and changing the setting or timing of the loop-taker in relation to the reciprocatory stroke of the needle, all as is well understood.

The primary object of the invention is an improved transmission of a character to compensate for or off-set the aforesaid induced rotation of the loop-taker incident to the rotative movements of its supporting turret.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a front elevation, part-sectioned, of a machine embodying the hereinafter described preferred form of the invention, Figs. 2 to 5 inclusive are enlarged part-sectioned views taken on the correspondingly numbered section lines of Fig. 1, Fig. 6 is an enlarged sectional view of the planetary transmission mechanism as seen in Fig. 1, and Fig. 7 is an enlarged sectional view on the line VII—VII of Fig. 1.

The illustrated machine embodying a preferred form of the invention is constructed with a frame having a bed 1, from one end of which rises a hollow standard 2 of a bracket-arm 3 overhanging the bed 1 and terminating at its free end in a head 4.

Journalized for rotation in suitable bearings pro-

vided in the bracket-arm 3 is a main or arm-shaft 5, carrying at one end thereof a conventional needle-bar actuating crank 6. The crank 6 is suitably connected by a link 7 to a tubular needle-bar 8, thereby to reciprocate the needle-bar vertically in the head 4.

An eye-pointed needle 9 is carried by the lower end of the needle-bar 8 for vertical reciprocation therewith, as well as for lateral jogging movements of the needle. The needle-supporting means of the present machine is commercially well known in eyelet-end buttonhole and eyeletting machine; said supporting means being fully illustrated and described in the prior U. S. Patents Nos. 1,372,473, March 22, 1921, and Re. 15,324, April 4, 1922, to which reference may be had for a complete understanding of the details of construction of the needle-supporting means.

As in the prior patented constructions, the needle 9 derives its lateral jogging movements from a rod 10 journaled for vertical reciprocation in the head 4. In the present machine, however, the rod 10 is operatively connected to one arm of a bell-crank lever 11, of which the other arm has a ball-joint connection with one end of a horizontally disposed connecting rod 12. The other end of the connecting-rod 12 is similarly connected to the forward end of a horizontally vibratory lever 13 pivotally secured upon the machine frame by a fulcrum-stud 14. Between its ends, the lever 13 is operatively engaged by a cam 15 carried by a vertically disposed rotary shaft 16 journaled in suitable bearing bosses provided upon the machine frame. The cam-shaft 16 carries a spiral-gear 17 engaged by a pinion 18 secured upon the main or arm-shaft 5; the ratio of the pinion 18 and spiral-gear 17 being such that the arm shaft 5 rotates twice for each rotation of the cam-shaft 16. The details of the transmission by which the needle-supporting means is progressively rotated form no part of the present invention and it will be sufficient to note that for the purposes of illustration such transmission is shown as including bevel gears 19 and 20, the latter mounted on the end of a shaft 21 which is driven through bevel gears 22, 23 from a vertical shaft 24. This latter shaft is driven through bevel gears 25, 26 by a shaft 27, which, for convenience, is referred to herein as the step-by-step turret-rotating shaft.

Mounted on the main or arm shaft 5 is an eccentric 28, which may be of the construction fully illustrated and described in the prior U. S. Patent No. 2,029,278, dated January 28, 1936, to which reference may be had for full details. In the

present construction the function of eccentric 28 is to reciprocate a connecting rod 29 which, through crank 30, imparts a rocking motion to a shaft 31 suitably journaled in the bed frame. Through crank 32 and link 33, shaft 31 is coupled to the inner drive member 34 of a one-way drive clutch generally designated 35. The outer or race member of the clutch, designated 36, is secured to the turret-rotating shaft 27. As will be understood, counter-clockwise movement (as viewed in Fig. 7) of the inner member 34, through balls 37, drives the outer or race member and shaft 27. Clockwise movement of member 34, on the other hand, releases balls 37 and imparts no motion to the race member or to shaft 27. To insure that shaft 27 remains stationary during such clockwise movements of member 34, a suitable brake may be provided, being indicated in the present instance as comprising an identical but reversely-mounted one-way drive clutch generally designated 38 (see Fig. 1).

Thus, rotation of the main or arm shaft 5 imparts the above-described reciprocating and lateral jogging movements to the needle and also a step-by-step rotary movement to the turret-rotating shaft 27. The latter, through shafts 24 and 21, imparts its progressive, rotary motion both to the needle-supporting means and also, through the transmission to be described below, to appropriate loop-taker supporting means, for the purpose, as above stated, of maintaining the correct directional approach of the beak of the loop-taker to the needle loop in all rotative positions of the needle.

Complemental to the needle 9 in the formation of lock stitches is a rotary loop-taker 39 of the horizontal-axis rotary hook type. The loop-taker 39 has its rotation axis disposed so that the needle-thread-loop seizing beak 40 of the loop-taker rotates in a plane substantially parallel to the plane of the lateral jogging movements of the needle 9. The loop-taker is carried by one end of a horizontally disposed rotary shaft 41 journaled in bearings 42, 43 upstanding from a suitable support or turret 44, the latter being mounted for rotation about a vertical axis for the purpose of bodily rotating the loop-taker and its shaft 41 in a horizontal plane. Depending from the center of the turret and journaled in the frame of the machine is a hollow shaft 45 to the lower end of which is secured a bevel gear 46 meshing with a bevel gear 47 mounted on the adjacent end of the step-by-step turret-rotating shaft 27. By this means the turret is progressively rotated in time with the progressive rotation of the needle.

Secured to the loop-taker shaft 41 is a bevel gear 48 meshing with a bevel or crown gear 49 mounted on the upper end of a shaft 50, which for convenience herein is referred to as the loop-taker drive shaft. For the purpose of imparting two complete turns to the loop-taker for each stroke of the needle, gear 49 bears a two-to-one ratio to gear 48.

As is well understood, the loop-taker beak 40 must not only maintain its correct angle of approach to the needle (to which end the progressive movements of the needle and loop-taker turret are synchronized as above described) but must also be so rotated on its own axis in timed relation to the reciprocatory stroke of the needle as always to be in position to seize the needle loop. However, the step-by-step rotation of the turret, unless compensated for, causes bevel gear 48 to roll on gear 49 and thereby induces in shaft 41 a

rotary movement in addition to that imparted to it by the loop-taker drive shaft 50, thereby changing the timing of the loop-taking approach of beak 40 in relation to the stroke of the needle.

According to the present invention, the above-mentioned additional or induced rotary movement of the loop-taker shaft, incident to the progressive rotation of the turret, is neutralized by the provision of special means for imparting an offsetting or compensating movement of like degree but opposite sense to the loop-taker drive shaft itself. In general, and as described in more detail below with reference to the preferred form illustrated, such means comprises a planetary transmission incorporating a drive train, which includes a driver, a driven member and connections from the driven member to the loop-taker drive shaft. One member of the drive train is supported by what, in effect, constitutes a planetary cage member and means is provided for transmitting the motion of the shaft 27 to such cage member. Thus, the cage-supported member is caused to roll on its driver, and the supplemental motion thus induced may be applied to the loop-taker drive shaft to impart to the loop-taker an equal, opposite and hence neutralizing rotative force to that induced by the rotation of the turret.

The preferred planetary transmission is illustrated particularly in Figs. 1 and 6 of the drawings. The drive for this transmission includes a pulley 51 mounted on the arm shaft 5, belt 52 and a second pulley 53 mounted on a power shaft 54 which is journaled in the machine frame below the bed-plate 1. The main driver of the planetary transmission comprises a slightly coned gear 55 secured to the power shaft 54. Meshing with the gear 55 is a like conical gear 56 secured to a shaft 57 mounted at an acute angle to the axis 40 of shaft 54 in a journal support 58. The journal support 58 is shown as a boss formed on the web of a gear 59 which is coaxial with the shaft 54; said gear 59 constituting the cage member of the planetary system and being journaled for free rotation on the shaft 54 adjacent the conical gears 55, 56. The end of the shaft 57 remote from the gear 56, i. e. the left-hand end of shaft 57 as viewed in Fig. 1, is provided with a universal or ball-driving head 60 carried by and in driving engagement with a sleeve 61 secured to a shaft 62, which, through bevel gears 63, 64 rotates the loop-taker drive shaft 50. To the extent thus far described, and so long as gear 59 is stationary, it will be seen that the planetary transmission operates merely to transmit the rotation of the main or arm shaft 5 to the loop-taker drive shaft 50. However, the rotation of shaft 57, and hence that of the loop-taker drive shaft, is modified by applying the step-by-step movement of shaft 27 to the cage member or gear 59, whereby conical gear 56 is caused to roll on its meshing conical gear 55. There is thus superimposed on shaft 57 (and hence the loop-taker drive shaft 50) a supplemental motion additional to that imparted to it by the rotation of shaft 54; and, by appropriate gear selection, this supplemental motion is caused to be of such a degree, and operates in such direction, as to neutralize the above-described induced rotation tending to be imparted to the loop-taker shaft 41 in response to the progressive rotation of turret 44. As shown, a pinion 65 secured to the turret-rotating shaft 27 meshes with and transmits the progressive rotation of shaft 27 directly to gear 59, i. e. to the cage member of the planetary transmission. Thus the

timing of the rotation of the loop-taker in relation to the reciprocation of the needle is preserved and is in no wise disturbed by the progressive rotation of the turret.

The operation of each group of elements having been brought out in connection with the description of the parts, no further elaboration will be necessary, it being understood, of course, that the principles of the invention are capable of embodiment in various forms within the limits of the accompanying claims. While by no means essential to the accomplishment of the main object of the invention, the preferred form has sundry advantages which will be recognized by those skilled in the art. Noteworthy, for example, is the fact that only a minimum number of gears is required in the described planetary system, that it does not incorporate any double, right-angle drives of the common differential type, that it lends itself to embodiment in compact form, and that the organization of this transmission is such as to adapt it to high speed, trouble-free operation.

Having thus set forth the nature of the invention, what I claim herein is:

1. In a sewing machine loop-taker mechanism having a rotary loop-taker shaft and a loop-taker drive shaft geared thereto, a turret supporting the rotary loop-taker shaft, and a turret-rotating shaft operatively connected for rotating the turret, the combination therewith of a planetary transmission comprising a power shaft, an externally toothed cage member rotatably journaled coaxially of said power-shaft, a driven shaft having a journal support in the cage member and mounted with its axis at an acute angle to the axis of the power shaft, meshing conical gears secured respectively to said power and driven shafts adjacent the cage member, a gear secured to the turret-rotating shaft and meshing with the cage member teeth to impart the rotary movement of the turret-rotating shaft to the cage member, a universal joint sustaining the end of the driven shaft remote from the said conical gear thereon, means for transmitting the rotary motion of said remote end of the driven shaft to the loop-taker drive shaft, means for imparting continuous rotation to the power shaft, and means for rotating said turret-rotating shaft.

2. In a sewing machine loop-taker mechanism having a rotary loop-taker shaft and a loop-taker drive shaft geared thereto, a turret supporting the rotary loop-taker shaft, and a step-by-step drive shaft for progressively rotating the turret, the combination therewith of a planetary transmission comprising a power shaft, a rotary cage member journaled coaxially of said power-shaft, a driven shaft having a journal support in the cage member and mounted with its axis at an acute angle to the axis of the power shaft, meshing conical gears secured respectively to said power and driven shafts adjacent the cage member, means for imparting the progressive rotary movement of the step-by-step drive shaft to the cage member, a universal joint sustaining the end of the driven shaft remote from the said conical gear thereon, means for transmitting the rotary motion of said remote end of the driven shaft to the loop-taker drive shaft, and means for simultaneously imparting continuous rotation to the power shaft and progressive rotation to the step-by-step drive shaft.

3. In a sewing machine loop-taker mechanism having a rotary loop-taker shaft and a loop-taker drive shaft geared thereto, a turret supporting

the rotary loop-taker shaft, and a step-by-step drive shaft for progressively rotating the turret, the combination therewith of a planetary transmission comprising a power shaft, an externally toothed cage member journaled thereon, a driven shaft having a journal support in the cage member and mounted with its axis at an acute angle to the axis of the power shaft, meshing conical gears secured respectively to said power and driven shafts adjacent the cage member, a gear secured to the step-by-step drive shaft and meshing with the cage member teeth to impart the progressive rotary movement of the step-by-step drive shaft to the cage member, means for transmitting the rotary motion of that end of the driven shaft remote from the said conical gear thereon to the loop-taker drive shaft, and means for simultaneously imparting continuous rotation to the power shaft and progressive rotation to the step-by-step drive shaft.

4. In a sewing machine loop-taker mechanism having a rotary loop-taker shaft and a loop-taker drive shaft geared thereto, a turret supporting the rotary loop-taker shaft, and a step-by-step drive shaft for progressively rotating the turret, the combination therewith of a planetary transmission comprising a power shaft, a cage member journaled thereon, a driven shaft having a journal support in the cage member and mounted with its axis at an acute angle to the axis of the power shaft, meshing conical gears secured respectively to said power and driven shafts adjacent the cage member, means for imparting the progressive rotary movement of the step-by-step drive shaft to the cage member, means for transmitting the rotary motion of that end of the driven shaft remote from the said conical gear thereon to the loop-taker drive shaft, and means for simultaneously imparting continuous rotation to the power shaft and progressive rotation to the step-by-step drive shaft.

5. In a sewing machine loop-taker mechanism having a rotary loop-taker shaft and a loop-taker drive shaft geared thereto, a turret supporting the rotary loop-taker shaft, and a turret-rotating shaft operatively connected for rotating the turret, the combination therewith of a planetary transmission comprising a power shaft, a cage member journaled coaxially of said power-shaft, a driven shaft having a journal support in the cage member and mounted with its axis at an acute angle to the axis of the power shaft, meshing conical gears secured respectively to said power and driven shafts adjacent the cage member, means for imparting the rotary movement of the turret-rotating shaft to the cage member, and means for transmitting the rotary motion of that end of the driven shaft remote from the said conical gear thereon to the loop-taker drive shaft.

6. In a sewing machine loop-taker mechanism having a rotary loop-taker shaft and a loop-taker drive shaft geared thereto, a turret supporting the rotary loop-taker shaft, and a turret-rotating shaft operatively connected for progressively rotating the turret, the combination therewith of a planetary transmission comprising a power shaft, a rotatable cage member, a driven shaft having a journal support in the cage member and mounted with its axis at an acute angle to the axis of the power shaft, drive means coupling said power and driven shafts at a point adjacent said journal support, means for imparting the rotary movement of the turret-rotating shaft to the cage member, and means for transmitting the

rotary motion of the said driven shaft to the loop-taker drive shaft.

7. In a sewing machine loop-taker mechanism having a rotary loop-taker shaft and a loop-taker drive shaft geared thereto, a turret supporting the rotary loop-taker shaft, and a turret-rotating shaft operatively connected for rotating the turret, the combination therewith of a planetary transmission comprising a power shaft, a rotatable cage member, a driven shaft having a journal support in the cage member and mounted with its axis at an acute angle to the axis of the power shaft, drive means coupling said power and driven shafts, means for imparting a rotary motion to said cage in time with said turret-rotating shaft, and means for transmitting the rotary motion of the said driven shaft to the loop-taker shaft.

8. In a sewing machine loop-taker mechanism having a rotary loop-taker shaft and a loop-taker drive shaft geared thereto, a turret supporting said rotary loop-taker shaft, and a turret-rotating shaft operatively connected for rotating the turret, the combination therewith of a planetary gear transmission incorporating a gear train including a rotary driver, a driven gear, connections from the driven gear to the said loop-taker drive shaft, a rotary cage member supporting one member of the gear train, said cage member comprising a toothed gear having its axis of rotation coincident with the rotation-axis of said rotary driver, and means for transmitting the motion of said turret-rotating shaft to said cage member.

9. In a sewing machine loop-taker mechanism having a rotary loop-taker shaft and a loop-taker drive shaft coupled thereto, a turret supporting said rotary loop-taker shaft and a turret-rotating shaft operatively connected for rotating the turret, the combination therewith of a planetary transmission comprising a drive train including a rotary driver, a driven member, connections from the driven member to the said loop-taker drive shaft, a rotary cage member comprising a toothed gear supporting one member of the drive train, said gear being disposed coaxial with said rotary driver, and means for transmitting the motion of said turret-rotating shaft to said cage member.

10. In a sewing machine loop-taker mechanism having a rotary loop-taker shaft and a loop-taker drive shaft geared thereto, a turret supporting the rotary loop-taker shaft, and a turret drive shaft, the combination therewith of a planetary transmission comprising a power shaft, a rotary cage member journaled coaxially of said power shaft, a driven shaft having a journal support in the cage member and mounted with its axis at an acute angle to the axis of the power shaft, meshing conical gears secured respectively to said power and driven shafts adjacent the cage member, means for imparting the motion of the turret drive shaft to the cage member, and means for transmitting the motion of the said driven shaft to the loop-taker drive shaft.

11. In a sewing machine loop-taker mechanism having a rotary loop-taker shaft and a loop-taker drive shaft geared thereto, a turret supporting the rotary loop-taker shaft, and a turret drive shaft, the combination therewith of a planetary trans-

mission comprising a power shaft, a rotatable cage member, a driven shaft having a journal support in the cage member and mounted with its axis at an acute angle to the axis of the power shaft, meshing conical gears secured respectively to said power and driven shafts adjacent the cage member, means for imparting the motion of the turret drive shaft to the cage member, and means for transmitting the motion of the said driven shaft to the loop-taker drive shaft.

12. In a sewing machine loop-taker mechanism having a rotary loop-taker shaft and a loop-taker drive shaft geared thereto, a turret supporting said rotary loop-taker, and a turret drive shaft, the combination therewith of a planetary gear transmission incorporating a gear train including a driver, a driven gear, connections from the driven gear to the said loop-taker drive shaft, a rotary cage member supporting one member of the gear train with the axis of such member at an angle to the plane of rotation of the cage member, and means for transmitting the motion of the turret drive shaft to the cage member.

13. In a loop-taker mechanism for sewing machines, a turret journaled for rotation about a vertical axis, a horizontally disposed loop-taker shaft rotatably journaled in said turret, a vertically disposed loop-taker drive shaft rotatable relatively to said turret, gears connecting said loop-taker drive shaft to said loop-taker shaft, a turret-rotating shaft operatively connected for rotating said turret, and loop-taker drive shaft rotating means comprising a rotary driver-gear, a rotary cage-member gear having its axis of rotation coincident with the rotation-axis of said driver-gear, a driven gear engaged by said driver-gear and carried by said cage-member gear for rotation relatively thereto and for travel circumferentially of said driver-gear, connections with said driven gear for rotating said loop-taker drive shaft, and means for rotating said cage-member gear from said turret-rotating shaft.

14. In a sewing machine, in combination, a vertically reciprocating needle having laterally vibratory movements in an orbital path, means for actuating said needle, a horizontal-axis rotary loop-taker complementary to said needle in the formation of stitches, a turret journaled for rotation about a vertical axis, a horizontally disposed loop-taker shaft rotatably journaled in said turret for bodily movement of the loop-taker in an orbital path corresponding to the orbital path of the needle, a loop-taker drive shaft geared to said loop-taker shaft, a turret-rotating shaft operatively connected for rotating said turret, and a planetary gear transmission for rotating said loop-taker drive shaft, said transmission including a rotary driver-gear, a rotary cage-member gear having its axis of rotation coincident with the rotation-axis of said driver-gear, a driven gear engaged by said driver-gear and carried by said cage-member gear for rotation relatively thereto and for travel circumferentially of said driver-gear, connections with said driven gear for rotating said loop-taker drive shaft, and means for rotating said cage-member gear from said turret rotating shaft.

ARTHUR N. HALE.
